The ornamental design for a compression hosiery comfort pad, as shown and described.

(58) **Field of Classification Search** D2/500–508,

DESCRIPTION

D2/610–624, 171, 200.1, 980, 983, 987, 992,

FIG. 1 is a top right side perspective view of a compression hosiery comfort pad on a leg of a user showing my new design typically with the elastic band at the top mounted on the upper thigh or below the knee with the broken line disclosure of the compression hosiery fitting on top of the compression hosiery comfort pad of a user leg and the compression hosiery on the leg being for illustration purposes only and forming no part of the claimed design;

D2/993; D29/120.1, 121.1; 2/16, 17, 59,

2/67; D24/190; D21/804; D11/1–25, 32,

D11/93, 94; 602/19; 59/78, 79.2; 63/1.11,

63/3, 3.1, 3.2, 5.1, 7–11; D10/32

FIG. 2 is a top plan view of the outer side of a compression hosiery comfort pad shown in FIG. 1 in a flat condition;

See application file for complete search history.
